UNITED STATES PATENT OFFICE.

CHARLES RICHARD EDOUARD WULFF, OF PARIS, FRANCE.

MEANS AND APPARATUS FOR PROPELLING AND GUIDING BALLOONS.

SPECIFICATION forming part of Letters Patent No. 363,037, dated May 17, 1887.

Application filed May 24, 1886. Serial No. 203,078. (No model.) Patented in France April 21, 1886, No. 175,662.

To all whom it may concern:

Be it known that I, CHARLES RICHARD EDOUARD WULFF, of Paris, in the Republic of France, have invented a new or Improved 5 Means and Apparatus for Propelling and Guiding Balloons, (for which I have obtained Letters Patent of France for fifteen years, dated April 21, 1886, No. 175,662;) and I do hereby declare that the following is a full and exact 10 description thereof, reference being made to the accompanying drawings.

All attempts heretofore made to guide or steer balloons have comprised mechanical, electric, or other motors for imparting the 15 necessary speed and direction to the propelling parts. Attempts in this direction have generally been unsuccessful by reason of the weight of the motor and its accessories, and because the propelling and guiding parts are only im- 20 perfectly suited to the medium in which they are placed and against which they have to take their bearing. By this present invention the mechanical motor and propelling and guiding arrangements are replaced by a living motor 25 or motors taken from the flying classes of birds—such as, for example, one or more eagles, vultures, condors, &c. By means of suitable arrangements (clearly shown in the annexed drawings) all the qualities and powers 30 given by nature to these most perfect kinds of birds may be completely utilized.

The invention consists in details of construction and combinations of parts, as will be more fully hereinafter set forth.

35 In the drawings hereto annexed, Figure 1 is an elevation of an air-balloon with living propellers in accordance with this invention. Fig. 2 is a plan with the parachute removed. Fig. 3 is a transverse section of the same, and 40 Fig. 4 a perspective view of the harness for connecting the birds to the balloon.

The balloon *a* may be of any suitable form and dimensions. It should be adapted to fulfill in the best possible way all the conditions 45 indicated by theory and experience for obtaining the maximum speed of translation and perfectly stable equilibrium. The gas-cham- bers are placed in front and behind. Their sizes are determined by the number of persons 50 to be carried, and by the specific gravity of the materials and accessories entering into the

constitution of the balloon. A car, *b*, is suspended to the balloon by means of a net and a metallic frame, *c c*, which connects these two principal parts rigidly together. In the car *b* is placed the aeronaut, who has charge of the 55 whole apparatus, and a reservoir of gas may also be placed therein to provide for leakages.

At the upper part is placed a floor, *d*, which carries the overseer or person working the apparatus. This floor, which is shown of circular form, has its center placed in the vertical plane, which contains the center of gravity of the whole apparatus. A mast, *f*, is securely 60 fixed in the center of the floor. 65

On the floor *d* rests, at any required height, a circular rail, *g*, concentric with the mast. On this rail roll four flanged rollers, *h*, mounted loosely on gudgeons on the ends of two arms, *k k'*, forming a cross. The boss *i*, toward 70 which the arms *k k'* converge, fits freely on the mast *f*. A sleeve, *j*, connects this boss to the hand-wheel *m*, placed at a suitable height. By moving the hand-wheel *m* in one direction or the other the cross *k k'* is turned round to 75 the right or to the left.

Besides the rollers *h* the ends of the cross *k k'* carry supports or standards *n*, which rise sufficiently high to be connected by hinges with the four corsets or metallic frames *p*, in 80 which are secured by bands and shoulder-straps *p'* the birds *x*, intended to draw and direct the balloon.

The corsets or harnesses *p* have forms and dimensions appropriate to the bodies of the 85 birds chosen, such as eagles, vultures, condors, &c. The straps or girts *p'* secure the birds firmly, but leave their wings in perfect liberty. These corsets are capable of pivoting forward or backward round the axis of the hinges *l*. 90 These pivotings are effected on all four corsets *p* at the same time by an arrangement of two rollers, *r r'*, carried in suitable bearings bolted to the cross *k k'*. These rollers, actuated simultaneously by the crank *q*, transmit the desired movements to the corsets *p* by means of cords or ropes *s s'*—one producing the forward oscillation and the other the backward. Ratchet wheels and pawls retain the rollers *r r'* in the required positions. 95

100 It will now be understood that as the balloon floats in the air the man placed on the

floor *d* can easily cause the cross *k k'* to turn by means of the hand-wheel *m*, and, with the cross, the birds *x*, so as to utilize their flight in the direction of the axis of the balloon, or 5 in any other direction he desires. On the other hand, by working the rollers *n n'* he can direct the flight of the birds upward or downward. The result of these arrangements is 10 to produce the motion and direction of the balloon desired by the conductor, whether for going forward or backward, in a right line, to the right or to the left, or for ascending or descending.

15 It may be observed that the birds have only to fly, the direction of their flight being changed by the conductor quite independently of their own will.

The director or conductor in the car *b* may 20 direct the person on the floor *d* by means of a speaking-tube, *t*, or other suitable means. When the apparatus stops, the birds rest on the stages *u u'*, arranged behind them and moving with the cross *k k'*. A net or nets, *v*, 25 is then lowered to prevent the birds from flying. A rope ladder, *w*, enables the aeronauts to ascend from the car *b* to the floor *d*, or to descend from the floor to the car. The mast *f* serves to support a parachute, *y*, which protects the birds and serves especially to regulate the descent of the balloon.

The balloon should always remain as much as possible in stable equilibrium, both when 30 on the ground and when floating in the air. 35 No weight should be left to be supported by the harnessed birds, so that the whole of their flying power may be utilized for advancing or guiding the balloon. A store of ballast enables the conductor to obtain this result constantly.

When it is on the ground, the balloon rests on tripods *z z'*, connected to the fore and hinder parts of the balloon, and furnished at the feet with elastic devices—such as springs, for example—to prevent or deaden shock. These 45 tripods *z z'* are connected to one another or to the car *b*. They form a solid and elastic whole, capable of resisting obstacles encountered. The charging and recharging of the balloon with gas is effected by the piping *T*, and generally by any known means and processes.

Finally, I observe that I can, without changing the principle of my invention or materially modifying the means already described for carrying it into execution, place the entire 55 mechanical apparatus for supporting and directing the birds under the bottom of the car *b*. This arrangement will possess the advantages of increasing the stability and of permitting a single aeronaut to raise the balloon. 60

I do not claim a device for holding birds that are to carry and hold suspended a car or other aerial vehicle. Birds have not the power to do this for any reasonable length of time.

I claim—

1. In a balloon, the combination of the floor *d*, circular railway *g*, rollers *h*, cross *k k'*, boss *i*, steering-sleeve *j m*, standards *n*, and harnesses *p*, substantially as herein shown and described. 70

2. The net *v*, combined with the bird-harness *p* and stage *u*, substantially as herein shown and described.

CHARLES RICHARD EDOUARD WULFF.
